UNITED STATES PATENT OFFICE.

GEORGE H. HOLLAND, OF ST. LOUIS, MISSOURI, ASSIGNOR TO THE BRIDGE & BEACH MANUFACTURING COMPANY, OF SAME PLACE.

DESIGN FOR A STOVE.

SPECIFICATION forming part of Design No. 22,575, dated June 27, 1893.

Application filed May 26, 1893. Serial No. 475,644. Term of patent 7 years.

To all whom it may concern:

Be it known that I, GEORGE H. HOLLAND, a citizen of the United States, residing at St. Louis, State of Missouri, have invented and 5 produced a new and original Design for Stoves, of which the following is a full, clear, and exact description, reference being had to the accompanying drawing, wherein the figure represents a perspective view of a stove ornamented with my new design.

The design relates particularly to an upright, square-shaped stove, and consists in the shape and ornamentation of its several component parts, as will hereinafter be described.

15 The base is square-shaped, and rests upon a sub-base, from the corners of which the legs project, said legs being ornamented on their outwardly-curving surfaces with a leaf. Arranged at each side of the legs on the sub-base is a large scroll, having several smaller scrolls and a spray leading therefrom, the two large scrolls on each side curving upwardly and across to meet each other to form a panel, in which panel are leaves having their stems 20 crossed. Projecting laterally from the upper side of the base are foot-rests, ornamented on their ends at the upper sides with scrolls.

25 The ash-pit door is provided with the usual draft opening, between, and on each side of which, it is ornamented with scrolls. At the junction of the ash-box and the base at the sides of the stove, are arranged a series of concave beads. At the front and sides of the stoves, above the ash-box, project outwardly 30 and downwardly, flanges, which are ornamented with a representation of inverted

shells. On the front of the stove, above this flange, is a door having the usual openings. At the sides of the stove, above the flanges, are arranged in panels, fan-shaped scrolls. 40 Above this door in the front of the stove and the side panels, are convex horizontally-disposed panels, which are ornamented with scrolls meeting each other at the center thereof, of which scrolls have leading therefrom to 45 each side of the panels, smaller scrolls. The front of the stove above this last-named panel, is provided with a door having two rows of openings, beneath which door is arranged a scroll. The sides of the stoves above the 50 panels are ornamented on the corners with scrolls, in the middle of which side portions are arranged square-shaped scrolls. The upper portion of the stove body is ornamented with beads and a band, which band is ornamented with scrolls. The top is dome-shaped, being ornamented with a web-work of scrolls, as shown. On the top of this dome is a cylindrically-shaped urn, the body of which is ornamented by flowers in full bloom and their 55 leaves.

What I claim is—

The herein-described design for stoves, substantially as shown.

In testimony whereof I hereunto affix my 65 signature, in presence of two witnesses, this 17th day of May, 1893.

GEO. H. HOLLAND.
